CLAIM

We claim the ornamental design for a combined polymerase chain reaction multi-well plate and plate of caps, as shown and described.

DESCRIPTION

FIG. 1 is a top plan view of a combined polymerase chain reaction multi-well plate and plate of caps with the multi-well plate portion shown separately for clarity of illustration; FIG. 2 is a detailed view of encircled area 2 of FIG. 1; FIG. 3 is a top plan view of a single strip of the combined polymerase chain reaction multi-well plate and plate of caps, with the single strip of the multi-well plate portion shown separately for clarity of illustration; FIG. 4 is a side view of the combined polymerase chain reaction multi-well plate portion; FIG. 5 is a top perspective view of the combined polymerase chain reaction multi-well plate portion; FIG. 6 is a top plan view of a combined polymerase chain reaction multi-well plate and plate of caps showing our new design, with the plate of caps portion shown separately for clarity of illustration; FIG. 7 is a detailed view of encircled area 7 of FIG. 6; FIG. 8 is a top plan view of the plate of caps; FIG. 9 is a side view of the plate of caps; FIG. 10 is a top perspective view of the plate of caps; and, FIG. 11 is a side view of the combined polymerase chain reaction multi-well plate and plate of caps showing our new design.

The broken lines in FIGS. 1, 3, 5, 6 9 and 10 depict portions of the combined polymerase chain reaction multi-well plate and plate of caps that form no part of the claimed design.
